Primary Examiner—M. H. Tung(74) *Attorney, Agent, or Firm*—Joseph C. Gil; James R. Franks(57) **CLAIM**

The ornamental design for a rigid support for a thin film data storage medium, as shown and described.

DESCRIPTION

FIG. 1 is a top perspective view of a rigid support for a thin film data storage medium showing our new design; FIG. 2 is a top plan view thereof; FIG. 3 is a top plan view of a second embodiment thereof; FIG. 4 is a bottom plan view thereof; FIG. 5 is a side elevation view thereof, as seen towards line 2—2, the opposite side is a mirror image; and, FIG. 6 is a front elevation view thereof, as seen towards line 1—1, the rear view is a mirror image.

The broken line drawing of the word “LOGO” in FIGS. 1-4 is for illustrative purposes only and forms no part of the claimed design.
